**CONTAINER ARRANGED WITH A SPOUT
IN ONE END**

Robert Nyden, Manhasset, N. Y., assignor, by direct and mesne assignments, to Continental Can Company, Inc., New York, N. Y., a corporation of New York

Application September 8, 1950, Serial No. 183,741

11 Claims. (Cl. 222—540)

This invention relates to a container arranged with a spout in an end wall of the container adapted to dispense liquids, such as lubricating oil, lighter fluid and the like, and particularly to securing the spout in the container end wall.

It has been the practice to secure a tapering spout in a container end wall by providing the container end wall with an annular discharge neck and the spout with an enlarged cup-like base at the larger end to fit over the container neck and the base is secured to the container neck by beading together juxtaposed portions of the neck and base.

Another known method of securing the tapering spout in the container end wall is to provide the end wall with a discharge neck arranged with an enlarged annular mouth portion and the spout with a shoulder spaced from the larger end positioned in the discharge neck of the container with the shoulder of the spout abutting the bottom wall of the enlarged annular mouth portion and secured therein by crimping the side wall of the enlarged annular mouth portion over the shoulder of the spout.

The disadvantages of these known methods of securing a spout in the end wall of a container are numerous and the most basic disadvantages are the number of steps required in forming the discharge neck and base portion of the spout which will increase the cost of manufacture; the discharge necks will prevent stacking of the container bodies upon each other for storage prior to securing the spouts to the container bodies; and it is not possible to produce a tight seal between the neck of the container and the spout.

It is an object of the present invention to secure a spout in the end wall of a container without the disadvantages of the prior known methods by providing a depressed portion in an end wall of the container arranged with a discharge opening and the walls of the depressed portion forming an annular channel or groove, and a spout having a flange adjacent to a cylindrical end portion of the spout engaged in the discharge opening with the flange above the groove in the depressed portion of the container end wall, and the spout forced into the depressed portion to flatten out the wall of the depressed portion adjacent to the discharge opening and impinge the edge of said wall against the cylindrical end portion of the spout below the flange.

It is another object of the invention to arrange the impinging edge of the depressed portion with spaced notches to provide a uniform snug fit between said edge and the cylindrical end portion of the spout.

It is a further object of the invention to arrange the underface of the spout flange with an annular groove to compensate for the compression of sealing means interposed between said underface and the depressed portion of the container end wall to provide a liquid tight seal between the spout and container end wall.

Another object of the invention is to provide the spout flange with a tapering or beveled edge corresponding to

2

the angle of inclination of the wall of the depressed portion adjoining the end wall of the container.

Other objects and advantages of the invention will be set forth in the detailed description of the invention.

5 In the drawing accompanying and forming a part of this application,

Figure 1 is a top view of a container body prior to the application of a spout thereto with a side portion of the container body broken-away.

10 Figure 2 is an elevational view of the top portion of the container with a sealing gasket assembled on a spout in position to be assembled in the depressed portion of the container end wall and half of the sealing gasket and spout and the depressed portion in section.

15 Figure 3 is a view similar to Figure 2 showing an initial step of applying pressure to the spout engaged in the discharge opening of the container whereby the gasket is forced into the annular groove in the underface of the spout flange.

20 Figure 4 is a view similar to Figures 2 and 3 showing the final step of applying pressure to the spout flange to secure the spout in the container end wall.

Figure 5 is a top view of a container having a spout secured therein by the steps shown in Figures 3 and 4.

25 Figure 6 is an elevational view of the assembled container shown in Figure 5 with portion of the container body broken-away.

Figure 7 is a fragmentary top view of the container body showing a modified form of depressed portion.

30 Figure 8 is a view similar to Figure 2 showing a modified form of sealing means applied to the depressed portion of the container end wall.

Figure 9 is a view similar to Figure 4 showing the spout secured in the container end wall with the modified form

35 of sealing means shown in Figure 8.

The embodiment of the invention shown in Figures 1 to 4, inclusive, comprises a sheet metal container body including a side wall 10 and end walls 11 and 12 secured to the opposite ends of the side wall in any suitable manner, such as rolling or crimping together the edge portions of said walls.

40 The end wall 11 constituting the top of the container is arranged with a depressed portion in the center of said wall comprising an inwardly tapering or declining wall portion 13 adjoining the end wall 12 and an outwardly tapering or inclining wall portion 14 extending from the wall portion 13 to a discharge opening 15 in the center of the depressed portion. The walls 13 and 14 form the depressed portion of annular channel or groove shape in cross-section, as shown at 16 in Figures 2 and 3. The depressed portion is of any desired shape and is shown as circular. The edge of the wall portion 14 forming the opening 15 is arranged with equidistantly spaced notches 17 for a purpose to be hereinafter described.

45 55 A spout is secured in the discharge opening 15 and comprises a tapering body 18 having a tapering bore 19 therein closed at the smaller end by the material of the spout, as shown at 20. The smaller end of the spout is also provided with a removable closure cap 21 to close the bore when the closed end 20 is punctured, as shown in Figure 6. The larger end of the spout is arranged with a cylindrical portion 22 having a beveled edge 23 to facilitate engagement of the spout into the opening 15. Between the body 18 and cylindrical portion 22, there is provided on the spout a flange having the upper-face sloping downwardly from the body 18 in an arcuate direction, as shown at 24, and the edge beveled inwardly or tapered from the upper-face to the underface, as shown at 25. The taper 25 corresponds to the angle of inclination of the depressed portion wall 13 to provide a tight fit

of the spout flange is arranged with an annular groove 26 between the edge 25 and portion 22 for a purpose to be hereinafter described. The material of the spout is softer than the material of the container, such as lead alloy or plastic such as polyethylene. The diameter of the spout portion 22 is slightly less than the diameter of the opening 15 in the position of the depressed portion 13, 14 shown in Figures 2 and 3 to permit ready engagement of said spout portion into the opening.

Prior to engaging the spout portion 22 in the opening 15, an annular sealing gasket 27 of suitable material, such as composite cork or rubber, is engaged on the spout portion 22 against the underface of the spout flange. The gasket will span the groove 26 and terminate inwardly of the edge formed by the underface and beveled edge 25, as shown in Figure 2.

The spout having the gasket thereon is engaged in the opening 15 and subsequently pressure is applied to the spout flange in a direction toward the container end wall 11. The pressure is shown as being applied by a hollow plunger 28 having a bore slightly larger than the larger end of the tapering spout body 18 and a head 29 adapted to engage the juncture between the spout body and upper face of the spout flange, as shown in Figures 3 and 4. The initial pressure applied to the spout flange partly forces a portion of the gasket 27 into the groove 26, as shown at 30 in Figure 3, and the continued pressure forces the depressed portion wall 14 into a flat or horizontal plane thereby decreasing the diameter of the opening 15 and impinging the edge of the depressed portion wall 14 forming said opening into the spout portion 22, as shown at 31 in Figure 4. At the same time, the gasket is compressed between the spout and depressed portion, as shown at 32 in Figure 4. The notches 17 facilitate decreasing the diameter of the opening 15 and assure a uniform impingement between the edge of the depressed portion 14 and the spout portion 22. The groove 26 will prevent excessive pressure from being applied to the depressed portion wall 14 and prevent forcing said wall 14 below the horizontal plane and collapsing of the container end wall 11 by receiving a portion of the gasket in the initial step of applying pressure without impairing the sealing efficiency of the gasket. When the pressure is removed from the spout flange by raising the plunger 28, the depressed portion wall 14 will remain in its horizontal position by the impingement of the edge thereof with the spout portion 22 and the stiffness of the material of said wall 14. The spout is also secured in the depressed portion of the container end wall by the tight fit between the beveled edge 25 of the spout flange and the depressed portion wall 13.

In Figure 7, there is shown a modified form of depressed portion in the container end wall 11 wherein the edge of the wall 14 forming the opening 15 is even or smooth and not interrupted by the notches 17, as shown at 33.

In Figures 8 and 9, the gasket 27 is replaced by a sealing compound applied to the groove formed by the depressed portion walls 13 and 14, as shown at 34 in Figure 8. When pressure is applied to the spout engaged in the opening 15 as described hereinbefore, the sealing compound is forced into the groove 26 and extends in a film between the depressed portion and spout, as shown at 35 in Figure 9.

Having thus described my invention, I claim:

1. In a container arranged with a spout in one end, a container body having side and end walls, one of said end walls being arranged with a depressed portion provided with a discharge opening, said depressed portion including a wall declining from the container end wall and a wall inclining from the declining wall to the discharge opening and said walls forming the depressed portion of groove shape in cross section, a spout having a body portion arranged at one end with a cylindrical portion and a flange

between the body and cylindrical portions, and sealing means compressed between the spout flange and depressed portion with the cylindrical spout portion engaged in the discharge opening and the edge of the depressed portion forming said opening impinged against the cylindrical spout portion by extending the inclining wall of the depressed portion in a horizontal plane.

2. A container arranged with a spout in one end as claimed in claim 1, wherein the spout flange is arranged with a beveled edge corresponding to the angle of inclination of the declining wall of the depressed portion.

3. A container arranged with a spout in one end as claimed in claim 1, wherein the edge of the depressed portion forming the discharge opening is arranged with spaced notches to facilitate decreasing the diameter of the discharge opening and assuring a uniform impingement of said edge with the cylindrical spout portion.

4. A container arranged with a spout in one end as claimed in claim 1, wherein the sealing means comprises an annular gasket slidably engaged on the cylindrical spout portion and abutting the spout flange.

5. A container arranged with a spout in one end as claimed in claim 1, wherein the sealing means comprises a sealing compound applied to the depressed portion.

6. A container arranged with a spout in one end as claimed in claim 1, wherein the face of the spout flange adjoining the cylindrical spout portion is arranged with an annular groove to receive a portion of the sealing means.

7. In a container, an end wall having a circular groove defined by an annular upwardly and outwardly sloping wall and a connecting annular upwardly and inwardly sloping inner wall, said inner wall terminating inwardly in a circular notched edge providing a spout receiving opening, and the juncture of said annular walls forming a rigid annular fulcrum about which the annular inner wall can be bent to a substantially horizontal position to bring about a spout impinging and gripping constriction of said spout receiving opening.

8. A spout comprising a body portion arranged at one end with a cylindrical portion, and a flange extending about the spout between the body portion and the cylindrical portion and defined by an upper face directed upward in the direction of projection of the body portion and a lower face directed downwardly in the direction of projection of the cylindrical portion and bearing substantially perpendicular relation to the axis of said cylindrical portion, said lower face having an annular groove therein and opening downwardly in concentric relation about the exterior of said cylindrical portion.

9. In a container arranged with a spout in one end, a container end wall arranged with a depressed portion provided with a spout mounting opening said spout having a body portion arranged at one end with a cylindrical portion received in said opening and a flange between the body and cylindrical portions, said depressed portion including an outer annular wall declining inwardly from the container end wall and an inner annular wall defining said opening and flattened from frusto-conical shape to cause the wall edge defining the opening to be constricted and impinge deeply in the spout portion received therein with the spout flange snugly engaging the flattened wall and substantially filling the depression.

10. In a container of the character described, a body having a wall equipped with a spout mounting recess defined by a flat annular seat wall having a spout receiving opening therethrough and an annular wall surrounding and defining the peripheral limits of said seat wall, and a spout comprising an elongated tubular body having a cylindrical extension projected through said opening and a flange extending outwardly from said extension and engaging at its peripheral edge snugly against said annular surrounding wall, the seat wall edge defining the opening therein biting deeply into the spout extension in a manner

for securely holding the extension in the opening and the spout flange against the seat wall.

11. A spout of deformable resilient plastic material comprising a slender tapering body portion having at one end a cylindrical portion larger in diameter than said body, and an annular flange disposed between the body and cylindrical portions and having the under face thereof directed downwardly in the direction of projection of said cylindrical portion and equipped with a downwardly opening annular groove providing an annular shoulder 10 immediately surrounding the cylindrical portion and an annular downwardly facing shoulder adjacent the periphery of the flange.
